UNITED STATES PATENT OFFICE.

CHARLES L. WIEDRICH, OF BUFFALO, NEW YORK, ASSIGNOR TO U. S. HAME COMPANY,
OF BUFFALO, NEW YORK.

DESIGN FOR A SHEET-METAL HAME-BODY.

44,623.

Specification for Design.

Patented Sept. 2, 1913.

Application filed July 25, 1912. Serial No. 711,569. Term of patent 14 years.

To all whom it may concern:

Be it known that I, CHARLES L. WIEDRICH, a citizen of the United States, residing at Buffalo, in the county of Erie and State of New York, have invented a new, original, and ornamental Design for a Sheet-Metal Hame-Body, of which the following is a specification.

In the accompanying drawing, Figure 1 shows a front elevation of a sheet metal hame body embodying the invention. Fig. 2 is a horizontal cross section, substantially centrally thereof and having the end portion broken away.

The hame body is formed from sheet metal and the front or outer face of this body is provided with beads or depressions

which are formed therein adjacent to its sides. These beads or depressions extend lengthwise of the front face of the hame body substantially parallel with the sides thereof throughout the greater portion of their length with their ends converging and meeting at a short distance from the upper and lower ends of the hame, so as to give the front face of the hame the appearance of having an ornamental panel formed therein.

I claim:

The ornamental design for a hame body, as shown and described.

CHARLES L. WIEDRICH.

Witnesses:
